COMBINED HOLDER AND POURER FOR A WINE BOTTLE OR THE LIKE

William A. Edwards, Los Angeles, Calif., assignor to Elmar Manufacturing Company, Chatsworth, Calif.

Filed June 8, 1973, Ser. No. 368,245

Term of patent 14 years

Int. Cl. D7—06

U.S. Cl. D7—70

FIG. 1 is a perspective view of a combined holder and pourer for a wine bottle or the like, showing my new design;

FIG. 2 is another perspective view thereof;

FIG. 3 is an enlarged scale side view thereof;

FIG. 4 is an enlarged scale front view thereof;

FIG. 5 is an intermediate scale top view thereof; and

FIG. 6 is an intermediate scale bottom view thereof.

I claim:

The ornamental design for a combined holder and pourer for a wine bottle or the like, substantially as shown.
